UNITED STATES PATENT OFFICE.

JOHN B. ALBERT, OF DANBURY, CONNECTICUT.

MUSIC-LEAF TURNER.

1,214,110.

Specification of Letters Patent.

Patented Jan. 30, 1917.

Application filed April 21, 1916. Serial No. 92,718.

To all whom it may concern:

Be it known that I, JOHN B. ALBERT, a citizen of the United States, residing at the city of Danbury, county of Fairfield, State of Connecticut, have invented certain new and useful Improvements in Music-Leaf Turners; and I do declare the following to be a full, clear, and exact description of the invention, such as will enable others skilled in the art to which it appertains to make and use the same.

This invention relates to certain new and useful improvements in leaf turners and particularly to that type depicted in my prior Patent No. 1,166,803, issued January 4, 1916, which is especially adapted for turning music leaves.

An important object is to provide an improved means, which dispenses with the metallic pump in my above noted patent, for creating a vacuum in a leaf-turning carrier for holding a leaf thereto.

A further aim resides in the provision of such a device which will efficiently operate at the will of the operator, said device being readily attached to the music support of a piano, or other music holder.

An additional and equally important object resides in the provision of a collapsible bulb with means for exerting pressure thereon to expel the air therefrom and thus create a vacuum.

The invention further resides in the salient features of construction, arrangements and combinations of parts described in detail in the following specification and succinctly pointed out in the appended claims, the preferred embodiment of the invention being illustrated in the accompanying drawings wherein—

Figure 1 is a front elevation of my device applied to the upper part of a music support; Fig. 2 is a rear view of the leaf turner alone, a portion of the carrier being omitted; Fig. 3 is a top plan view thereof; Fig. 4 is a horizontal section thereof on line 4—4 of Fig. 2, and Fig. 5 is a vertical section through the device on line 5—5 of Fig. 4.

I prefer to mount the present invention at the top or upper portion of the usual piano music support 1, as by brackets 2, and inclose part of the mechanism in a support or casing 3.

The carrier 4, which is tubular, is pivoted at 5 on the casing and provided on its free outer end with a rubber cup 6 in which a

vacuum may be created for "taking hold" of the music sheet 7. A gear part 8 is formed on the pivoted inner end of the carrier arm 4 and with this part mesh the teeth 9 of a mutilated gear 10 which comprises a pair of segmental portions, the teeth 11 of the gear being meshed with a segmental gear 12. This last gear is journaled between a pair of ears 13, formed on the casing 3, and fixed on the shaft 14 of the gear is an arm 15 having pin and slot connection 16 with the vertical arm 17 of a bell-crank lever 18, the latter being pivoted at 19 on said casing. A coiled spring 20, fixed to the shaft 21 of gear 10 and to the housing 22, integral with the gear, returns the latter to normal position after each operation.

A rubber tube or bulb 23 has its opened end expanded over a base 24, and connecting the interior of the bulb through the base with the tubular carrier and vacuum cup is a flexible length of tubing 25. The base 24 and tubing 25 thus constitute a means of communication between the bulb and carrier.

Fulcrumed on a standard 26, upstanding from the top plate of casing 3, is a compression lever 27, which has pivoted on its free end a bearing face 28, the latter being designed to force in the resilient and collapsible walls of the self-expanding body 23 and thereby expel the air from the latter and the carrier. Thus, it is obvious, that upon relieving the bulb from the pressure of the compression member 27, the tendency of the bulb to assume its normal shape will create a vacuum within the latter and the carrier sufficient to cause the vacuum cup 6 to adhere to the sheet of music.

The compression lever 27 is preferably curved and on the convex edge thereof is guided the forked end 29 of a second lever 30 which is pivoted to the casing at 31 and maintained in normal position against the compression lever by a back stop 32 resting on the casing, as depicted in Fig. 2. An arm 33 extends from the lever 30 to overlie the horizontal arm 34 of the bell-crank lever 18, and on the former arm is provided a lateral stud 35 with which the hooked terminal 36 of an actuator 37 may releasably engage.

The actuator is swingingly supported from the casing 3 by a link 38 and consists of two pivotally connected parts, the lower part or section being joined to a pedal or

other suitable member (not shown) by rod 39. Each part of the actuator has a shoulder 40 coöperating with a spring 41 to hold the actuator practically a rigid structure. 5 A pin 42 normally spaced above the arm 34 is adapted to engage the latter and through it swing the segmental gear 12 for operating the carrier. This pin is so spaced above the arm 34 that on exerting a downward pull on the actuator 37, the latter will initially effect a compression or collapsing of the bulb and then a swinging of the carrier. In this connection, it will be noted that pressure of the lever 27 on the 10 bulb must be removed before a vacuum can be formed, and to this end I provide means for disengaging the hook 36 from the stud 35 immediately prior to the pin 42 abutting the arm 34 for effecting a swinging of the carrier. This disengaging means comprises a dog 43 pivoted to the upper part of actuator 37 and normally resting on the supporting link 38. A lug or stop 44 projects from the dog to engage the upper part of actuator 37, as the latter moves downwardly, which stop prevents further relative movement between the pivoted elements. Consequently, continued relative movement between the dog 43 and link 38 20 will shove the hook 36 from over the stud 35 whereupon the bulb will immediately begin expanding to create a vacuum. Subsequent downward movement of the actuator will then effect operation of the carrier. 25 When the carrier has performed its office it is necessary to destroy the vacuum to release the sheet from the vacuum cup 6 to prevent the latter from turning the sheet back. Therefore, in the base 24 and 30 lower end of the bulb 23 is provided a vent 45 opening from the communicative means between the bulb and carrier. This vent is initially and normally closed by a valve 46 carried on one end of a lever 47, the latter being pivoted between its ends and within the casing as shown in Fig. 4. A spring 48 holds the valve normally seated. The larger segment of gear 10 is designed to strike the lever 47, when the carrier has 35 performed its function, and thus unseat the valve 46 to destroy the vacuum within the bulb and carrier. The latter is then free of the sheet to return.

From the foregoing it will be observed 40 that upon pulling the actuator down, four important steps are performed in the following sequence: the collapsing or compressing of the bulb; the subsequent release of the pressure exerted mechanically on the bulb; the swinging of the carrier; and the destruction of the vacuum previously created. The operation is entirely automatic outside of the depression of the actuator, and the single carrier will efficiently operate in adhering to successive

sheets without the provision of an independent carrier for each sheet.

The substitution of a rubber bulb for a pump such as is illustrated in my prior patent is more economical, the purpose it serves being equally as well performed. 70

What is claimed is:

1. In a leaf turner, a support, a swingingly mounted hollow leaf carrier, a self-expansible collapsible body communicatively connected with the carrier for creating a vacuum therein whereby a leaf will adhere to the carrier, and means operable in one continuous direction for effecting both a collapsing and releasing of the body. 80

2. In a leaf turner, a support, a swingingly mounted hollow leaf carrier, a self-expansible collapsible body communicatively connected with the carrier, a carrier-swinging means, means for collapsing and releasing the body for creating a vacuum in the carrier whereby a leaf will adhere to the latter, and a common actuator for the last two means initially free from the collapsible body. 85

3. In a leaf turner, a support, a swingingly mounted hollow leaf carrier, a self-expansible collapsible body communicatively connected with the carrier, means for compressing the body, means for swinging the carrier, an actuator for the last two means releasably engaging the body-compressing means, and means movable relative to the actuator for releasing the body-compressing means from the actuator for creating a vacuum in the carrier whereby a leaf will adhere to the latter. 90

4. In a leaf turner, a casing, a leaf carrier swingingly mounted thereon, a collapsible bulb, means of communication between the bulb and carrier whereby on collapsing and releasing pressure from the bulb a vacuum will be created in the carrier for causing a leaf to adhere to the latter, means for collapsing the bulb, and means automatically rendering the bulb-collapsing means inoperative prior to movement of the carrier. 105

5. In a leaf turner, a casing, a leaf carrier swingingly mounted thereon, a collapsible bulb normally expanded, means of communication between the bulb and carrier whereby on collapsing and releasing pressure from the bulb a vacuum will be created in the carrier for causing a leaf to adhere to the latter, and means for successively compressing and releasing the bulb and swinging the carrier. 115

6. In a leaf turner, a rubber bulb, a leaf carrier arm communicatively connected therewith, and means operable by a single movement in one direction to compress and release the bulb for creating a vacuous condition therein and in the carrier whereby a leaf will adhere to the latter. 125

7. In a leaf turner, a casing, a leaf carrier 130

swingingly mounted thereon, a vacuum cup on the carrier to which a leaf is caused to adhere when a vacuum is created therein, a collapsible vacuum producer, means of communication between the cup and vacuum producer, means for collapsing and releasing the latter to create a vacuum in the cup, means for swinging the carrier, and actuating means operable in one continuous and uninterrupted movement to actuate the last

10 two means.

8. In a leaf turner, a casing, a leaf carrier swingingly mounted thereon, a vacuum cup on the carrier to which a leaf is caused to adhere when a vacuum is created therein, a collapsible vacuum producer, means of communication between the cup and vacuum producer, means for collapsing the latter for subsequent release to create a vacuum in the cup, means for swinging the carrier, and continuously operating unitary means for successively actuating and releasing the collapsing means and subsequently actuating the leaf carrier swinging means.

25 9. In a leaf turner, a rubber bulb, a leaf carrier arm communicatively connected therewith, a compression lever normally supported by the bulb, and means releasably engaging the lever for exerting pressure thereon to compress the bulb and to subsequently remove the pressure therefrom to create a vacuum therein and in the carrier whereby a leaf will adhere to the latter.

30 10. In a leaf turner, a support, a leaf carrier swingingly disposed thereon, means for swinging the carrier, and a compressible self-expanding body communicatively connected with the carrier for creating a vacuum in the carrier whereby a leaf will adhere thereto, and means for successively compressing the body and operating the carrier swinging means in a single continuous operation.

35 11. In a leaf turner, a rubber bulb, a leaf carrier arm communicatively connected therewith, a compression lever normally supported by the bulb, means releasably engaging the lever for exerting pressure thereon to compress the bulb and to subsequently remove the pressure therefrom for creating a vacuum in the carrier whereby a leaf will adhere to the latter, and means operable by the first means subsequent to the release of the compression lever for swinging the carrier arm.

40 12. In a leaf turner, a support, a self-expanding collapsible body, a leaf carrier movably mounted on the support, means communicatively connecting the carrier and body whereby a vacuum created in the body will be created in the carrier also for causing a leaf to adhere to the latter, said means being provided with a vent, means initially closing the vent, and means for operating the carrier and opening the vent to destroy

the vacuum, said last means being initially free of the vent-closing means.

45 13. In a leaf turner, a support, a self-expanding collapsible body, a leaf carrier movably mounted on the support, means communicatively connecting the carrier and body whereby a vacuum created in the body will be created in the carrier also for causing a leaf to adhere to the latter, said means being provided with a vent, a valve initially closing the vent in said means, means initially free of the valve for operating successively the carrier and opening the valve, and means for collapsing the body and operating the last means.

50 14. In a leaf turner, a support, a leaf carrier swingingly mounted thereon, a gear part fixed to the pivoted end of the carrier, a gear journaled on the support and meshing with the gear part of the carrier, a bulb, means communicatively connecting the bulb and carrier whereby a vacuum created in the bulb will be formed also in the carrier whereby a leaf will adhere to the latter, said means being provided with a vent which, when opened, eliminates the vacuum, a valve initially closing the vent in said means and adapted to be opened by said gear, and means for operating the gear.

55 15. In a leaf turner, a casing, a bulb secured at its open end thereto and having its compression end outstanding from the casing, a compression member pivoted to the casing and normally resting on the compression end of the bulb, a hollow leaf carrier communicatively connected with the bulb, and means engaging and releasing the compression member for operating the latter to create a vacuous condition in the bulb and leaf carrier whereby a leaf will adhere to the latter.

60 16. In a leaf turner, a support, a leaf carrier swingingly mounted thereon, a gear part fixed to the pivoted end of the carrier, a gear journaled on the support and meshing with the gear part of the carrier, a bulb, means communicatively connecting the bulb and carrier whereby a vacuum created in the bulb will be formed also in the carrier to cause a leaf to adhere to the latter, said means being provided with a vent which, when opened, eliminates the vacuum, a valve initially closing the vent in said means and adapted to be opened by said gear, a swingingly mounted segmental gear meshing with the first gear for rotating the latter, a pivoted bulb-compressor, and means for swinging the bulb-compressor and segmental gear.

65 17. In a leaf turner, a support, a leaf carrier swingingly mounted thereon, a gear part fixed to the pivoted end of the carrier, a gear journaled on the support and meshing with the gear part of the carrier, a bulb, means communicatively connecting the bulb and carrier whereby a vacuum created in

- the bulb will be formed also in the carrier to cause a leaf to adhere to the latter, said means being provided with a vent which, when opened, eliminates the vacuum, a valve 5 initially closing the vent in said means and adapted to be opened by said gear, a swingingly mounted segmental gear meshing with the first gear for rotating the latter, a pivoted bulb compressor, means to swing the 10 bulb compressor including a releasable hook member, and means operable by said last means subsequent to being released from the bulb compressor for swinging the segmental gear.
- 15 18. In a leaf turner, a support, a leaf carrier swingingly mounted thereon, a gear part fixed to the pivoted end of the carrier, a gear journaled on the support and meshing with the gear part of the carrier, a bulb, 20 means communicatively connecting the bulb and carrier whereby a vacuum created in the bulb will be formed also in the carrier

to cause a leaf to adhere to the latter, said means being provided with a vent which, when opened, eliminates the vacuum, a valve 25 initially closing the vent in said means and adapted to be opened by said gear, a swingingly mounted segmental gear meshing with the first gear for rotating the latter, a pivoted bulb compressor, means to swing the 30 bulb compressor including a releasable hook member, a link supporting the hook member from the support, a kicker dog carried by the hook member for engaging the link, and means operable by said last means subsequent to being released from the bulb compressor for swinging the segmental gear.

In testimony whereof I affix my signature in presence of two witnesses.

JOHN B. ALBERT.
